UNITED STATES PATENT OFFICE.

CHARLES B. CLUTE AND FRANK B. NESSLING, OF CHICAGO, ILLINOIS, ASSIGNEES TO CLUTE MANUFACTURING CO., OF CHICAGO, ILLINOIS, A CORPORATION OF ILLINOIS.

DOOR CHECK AND HOLDER.

Application filed August 28, 1925. Serial No. 53,024.

This invention relates to a combined door check and holder, and is concerned particularly with certain features which tends to improve the operation and simplify the assembly of its several parts.

The device of our invention makes use of spring means which act conjointly with a fluid to govern the door movements. It includes an improved valve for controlling the flow of liquid consequent upon movement of the door. Such a valve is leak-proof and is readily adjustable, as desired. Additionally we have provided a by-pass element which serves also as a key to co-operate with a shiftable cam member. Other features which are incorporated into the device include an adjustable detent which co-operates with the door in such a manner as to permit the latter to swing freely past a normal movement limit. With features such as these, our invention is concerned, and with others also which will more fully hereinafter appear in the description and claims, taken in conjunction with the accompanying drawings wherein our invention is illustrated in the manner following.

Fig. 1 is a top plan view showing the check applied operatively to a door;

Fig. 2 is a detail in section taken on line 2-2 of Fig. 1;

Fig. 3 is a central vertical section through the device; and

Fig. 4 is a transverse section therethrough taken on line 4-4 of Fig. 3.

The door check proper includes a cylindrical body 5 from which are extended bracket arms 6 for attachment to a door A. Within the body are upper and lower chambers 7 and 8 respectively, separated by an annular shoulder 9 wherein is a threaded seat for accommodating a partition plate 10. Extending centrally through a hub in the partition plate is a spindle 11 which is surrounded by a suitable packing so as to prevent leakage of fluid along the spindle from one chamber to the other. A cover plate 12 is arranged over the upper body chamber, as shown.

A recess 14 extends longitudinally along an inner face of the walls surrounding the lower chamber. As shown in Fig. 4, this recess is substantially semi-circular in cross section so as to receive approximately one-half of a tubular stem 15. At its lower end this stem is rested upon a shoulder 16 formed

at the lower recess end, the upper end of the stem being proximate to the partition plate. There is also a transverse bore 17 near the upper stem end which intersects the longitudinal bore thereof, the purpose of which will presently appear. Fitted within the lower chamber is a hollow plunger 18 having exteriorly thereof a groove or recess for accommodating substantially one-half of the stem. In this manner the stem serves as a key to prevent the plunger from rotating within the chamber, while permitting free vertical movement thereof. Between the plunger bottom and the bottom of the check body is a compression spring 19 which tends always to raise the plunger. Through the plunger bottom, we have also provided a port 20 wherein is a ball check valve 21, as shown.

The interior of the plunger in its upper region is provided with a spirally arranged shoulder 22 forming one element of a cam. Co-operating therewith is a second element consisting of a collar 23 which is pinned or otherwise made fast to the spindle, and disposed upon the under side of the partition plate. Extending laterally from this collar is a head 24 adapted to rest upon the spiral shoulder 22 of the plunger, its vertical relation thereto being determined by the rotative position of the spindle.

Within the upper chamber of the casing we have provided a coiled spring 25 connected both with its walls and with a thimble 26 upon which is exerted a rotary force. This thimble which extends through the cover plate 12 carries on its outer end a ratchet disk 26a engaged by a dog 27 which is mounted on an arm 28, one end of which is pivoted to the spindle end, as shown. Upon the spindle extremity is threaded a nut 29 which assures retention of the parts in the assembled relation just described. At the opposite arm end is a pivotal connection 30 with a second arm 31 with which is associated an extensible rod 32, having one end pivotally connected as at 33 with a jamb B or other stationary support adjacent the door.

Exteriorly of the check body, we have provided an annular shoulder 34 whereon is rested a split collar 35 whose ends are outwardly turned to provide lugs 36 which may be drawn together by a screw 37, as shown in Fig. 1. In this manner, the collar may be

clamped tightly upon the casing in any desired rotative position. It is preferred that the cover plate 12 should overhang the casing slightly so as to project into an annular recess 38 of the collar, whereby to confine it in place. Only by removing the nut 29, may the cover plate be removed to permit disassembly of the collar 35 from the casing. Extending laterally from the collar and preferably at a point which is opposite the lugs 36 is a boss 39 wherein is a vertically extending chamber 40 (see Fig. 2) closed at one end by a screw-threaded plug 41. At the other chamber end an annular shoulder 42 may extend inwardly to confine in place a head 43 having a flange 44 which receives thrust from one end of a compression spring 45 whose opposite end bears against the plug 41. By this means we have provided in effect a spring button which projects normally from the boss, as shown. Preferably the outer face of the button is beveled as at 46 for yieldable engagement with a beveled abutment 47 which is carried on the under side of the arm 28. On account of the co-operation between this button and the abutment, we are able to swing the door to a point where the abutment member passes over the button to assume a position on the opposite side thereof. The door may not then be closed under the action of the spring and door check unless an extra pressure be applied sufficient to overcome the retarding effect of the button. The point in the door movement where the button will serve to resist closing movement thereof may be adjusted at will by loosening the screw 37 and then shifting the collar 35 around to a new position.

In order that closing movements of the door may be retarded desirably a fluid agent is employed. This is confined wholly within the lower chamber 8, and may flow freely through the opening 20 from the upper to the lower side of the plunger, but not reversely owing to the presence of the check valve 21. Liquid may also flow through the tubular key 15 except as prevented by a valve which presents a beveled stem 50 within the lateral bore 17. This stem is formed as an extremity upon a cone shoulder 51 carried on a head 52 from which is extended rearwardly a shank 53. The cone shoulder rests within a seat 54 formed in the walls of the check body adjacent which we have provided a recess for receiving a gasket 55. Bearing against the gasket and screw-threaded into the recess is a tubular nut 56 wherein is mounted a bushing 57 having a screw-threaded connection therewith. The inner bushing end abuts the proximate end of the valve head 52 whereby the shoulder 51 is held against its seat. We provide means, however, for adjusting the rotary position of the valve, the same consisting of

a crown 58 which is connected to the outer end of the shank 53. Manifestly the clearance in the passage 17 will depend upon the rotative position of the valve which, as above indicated, may be adjusted at will. By screwing in the bushing 57, the valve will be held against any accidental displacement from the position to which it has once been adjusted.

A valve answering to the above description is particularly effective in an environment of the kind here contemplated. Because of the manner in which its cone shoulder is held tightly against its seat, there can be no escape of liquid from within the casing. Also in case of any overhauling, the valve may be demounted by simply unscrewing the nut 56 following which the tubular key may also be pulled out, should this operation be desired. For reasons such as this, the door check of our invention possesses special advantages from a manufacturing and assembly standpoint.

We claim:

1. A door check having a chambered body, a spring pressed plunger slidable within the body, and a tubular key removably fitted between the plunger and body, the tubular key providing a by-pass for movement of fluid past the plunger from one chamber end to the other, substantially as described.

2. A door check having a chambered body, a plunger movably fitted within the body, a tubular key fitted between the plunger and body communicating with opposite ends of the chamber whereby fluid may move therethrough past the plunger, cam means associated with the plunger for advancing the same longitudinally within the chamber, and an arm connecting the cam with a door for controlling the movement of the latter, substantially as described.

3. A door check having a chambered body in which is a movable plunger, a key fitted between the body and plunger to prevent relative rotation therebetween, the key having a longitudinal passage communicating with opposite ends of the chamber, cam means associated with the plunger whereby to advance the same within the chamber, spring means for opposing such plunger movement, and a valve operatively associated with the key passage for controlling the flow of fluid therethrough, substantially as described.

4. A door check having a chambered body in which is mounted a plunger, a tubular key removably fitted between the plunger and body to prevent relative rotation therebetween, and a valve demountably associated with the body and having an operating portion thereof disposed within the key to control the passage of fluid therethrough, substantially as described.

5. A door check having a chambered body

- in which is a movable plunger, a key fitted between the body and plunger and provided with a longitudinal passage communicating with opposite ends of the chamber, and 5 means for securing the key against displacement comprising a valve which is extended in part within the key passage, and a valve mounting removably fitted to the body, substantially as described.
- 10 6. A door check having a chambered body with a plunger movable therein, a by-pass permitting liquid to flow from one chamber end to the other past the plunger, a valve associated with the by-pass comprising a 15 rotatable stem therewithin, a cone shoulder adjacent the stem, there being a cone seat therefor in the body wall, and means providing a mounting for the valve consisting of a tubular nut having a screw-threaded 20 connection with the body wall adjacent the seat, a bushing threaded into the nut, a head on the valve adjacent the cone shoulder, and a shank rearwardly of the head extending through the bushing, one bushing end being 25 engaged with the valve head to force the shoulder toward its seat, and means on the rear end of the shank operable for rotating the valve stem, substantially as described.
7. A door check having a chambered body 30 in which is mounted a plunger, there being a by-pass through which liquid may flow past the plunger from one chamber end to the other, a valve associated with the by-pass, including a rotatable stem which is disposed therein, a cone shoulder adjacent the stem, means in the check body providing a cone seat for the shoulder, and a pair of screw elements having their threads interengaged, one of said elements having a 35 screw-threaded connection with the valve 40
- body in a manner to support the valve in position and hold the shoulder against its seat, substantially as described.
8. In a door check, the combination with 45 spring means of a pair of pivoted arms extending therefrom to a fixed support, and means for arresting action of the spring means comprising a fixed beveled abutment carried on one arm, a movable spring-pressed button engageable therewith, and a 50 mounting for the button located to the side of the check body consisting of a collar surrounding the check and having clamping means for holding the same fixedly in a desired position of rotative adjustment thereupon, substantially as described.
9. A door check having a body within 55 which is spring means, a pair of arms acted upon by the spring means and connecting the body with a fixed support, a collar slidably fitted around the body and having clamping means for holding the same in a fixed position of adjustment thereupon, a chambered boss carried by the collar to the 60 side of the check body and provided at one end with an inturned shoulder, a flanged button confined partly within the boss chamber, a closure plug removably fitted to the opposite boss end, spring means exerting 65 opposing thrusts on the plug and button whereby the latter is normally projected exteriorly of the boss chamber, and an abutment carried by one of the arms and provided with a pair of oppositely formed surfaces for alternate engagement by the button in a manner which tends to arrest action 70 of the spring means within the check, substantially as described.
